UNITED STATES PATENT OFFICE.

MAURICE W. BRANTMAN, OF BROOKLYN, NEW YORK, ASSIGNOR TO REPUBLIC KNITTING MILLS, INC., OF NEW YORK, N. Y., A CORPORATION OF NEW YORK.

DESIGN FOR A KNITTED JACKET.

Application filed March 22, 1924. Serial No. 9,039. Term of patent 3½ years.

To all whom it may concern:

Be it known that I, MAURICE W. BRANTMAN, a citizen of the United States of America, and a resident of the borough of Brooklyn, Kings County, city and State of New York, have invented a new, original, and ornamental Design for Knitted Jackets, of which the following description, in connection with the accompanying drawing, is a specification.

Fig. 1 is a front elevation; and Fig. 2 is a rear elevation of a knitted jacket embodying my new design.

I claim as my invention:

The ornamental design for a knitted jacket as shown.

MAURICE W. BRANTMAN.
